UNITED STATES PATENT OFFICE.

EDWIN D. TILLSON, OF CHICAGO, ILLINOIS, ASSIGNOR TO ASSOCIATED ENGINEERS COMPANY, OF CHICAGO, ILLINOIS, A CORPORATION OF ILLINOIS.

LIGHTING-FIXTURE-CLEANING DEVICE.

1,415,065.

Specification of Letters Patent.

Patented May 9, 1922.

Application filed April 19, 1920. Serial No. 374,959.

To all whom it may concern:

Be it known that I, EDWIN D. TILLSON, a citizen of the United States, residing at Chicago, in the county of Cook and State of Illinois, have invented a certain new and useful Improvement in Lighting-Fixture-Cleaning Devices, of which the following is a full, clear, concise, and exact description, reference being had to the accompanying drawings, forming a part of this specification.

My invention relates to lighting fixtures and more particularly to lighting fixtures provided with means for cleaning the same.

The invention further relates to a lighting fixture wherein a means is provided for cleaning dust and dirt from certain parts of the same by devices operated from the pull cord of the light simultaneously with the operation of the switch controlling the light.

The invention more particularly relates to a means for wiping dust and dirt from the surfaces of a lighting fixture through which the light must pass or from which it is reflected and from a bulb associated with the same upon operating a pull cord, which may at the same time operate to turn the light on or off.

Further objects and advantages will appear from the following detailed description of the invention shown in the accompanying drawings, wherein similar parts are referred to by similar reference characters, and in which

Fig. 1 is a side elevation partly in section of one form of my improved lighting fixture;

Fig. 2 is an enlarged fragmentary sectional detail view thereof;

Fig. 3 is a transverse sectional view taken on the line 3—3 of Fig. 2;

Fig. 4 is a side elevation partly in section of another form of my improved lighting fixture;

Fig. 5 is a fragmentary sectional detail view of the lower portion of the fixture shown in Fig. 4;

Fig. 6 is a plan view of the actuating mechanism for this form of the device;

Fig. 7 is a side elevation partly in section of still another form of the improved lighting fixture;

Fig. 8 is a fragmentary sectional detail

view of the wiping mechanism used in this form of the invention, and

Fig. 9 is a fragmentary sectional detail view of an end of the wiping arm, said section being taken at right angles to that of Fig. 8.

Referring to Figs. 1 to 3 inclusive, my improved lighting fixture 11 comprises the reflector 12 made of porcelain enameled steel or in any other manner, a lamp socket 13 and socket cap 14, said cap being mounted in a suitable fitting 15 externally screw threaded to receive the cap at one end and internally screw threaded at the other end for receiving the fixture stem 16.

The reflector is clamped to the fitting 15 by a lock nut 17 screwed onto an externally screw threaded portion 18 of the fitting 15. The reflector is clamped between a pair of leather washers 19. The socket 13 is surrounded by a shell of metal or other suitable material 20 which is mounted for rotation on the socket cap at 21. The shell 20 acts as a drum to receive the rope or cord 22 by means of which it is rotated as will be clear from an examination of Fig. 1. The rotation of the drum caused by a pull of the cord 22 will be in a counter-clockwise direction (looking downwardly) as will be clear from an inspection of Figs. 1 and 3. A coil spring 23 is suitably mounted in the fitting 15 and the shell or drum 20 so as to be put under tension when the drum is rotated in a counter-clockwise direction as described above. The coil spring is shown in the drawings as being secured to the drum and fitting respectively by the insertion of the ends thereof in the holes 24 and 25 in the members 20 and 15. In order to provide a bearing against the lower part of the socket for the drum 20 the knob-like members 26 are secured thereto in any suitable manner as by riveting. These are provided in spaced relation about the drum and act so as to properly space the drum and socket at the lower ends thereof.

The extreme lower end portion of the drum 20 is provided with a bead 27 and a ring 28 is mounted thereon so as to be free to rotate thereabout. The drum 20 is provided with a spring finger 29 secured to the inner face thereof in any suitable manner as by rivets. The beveled finger or dog 30 is provided on the end of the member 29 and

60

75

80

85

90

100

105

is adapted to project through an opening 31 in the member 20 due to the spring action of the member 29.

The ring 28 is provided with suitable 5 openings 32 and it will be evident that when any one of the openings 32 coincides with the openings 31 the finger 30 will be pressed into said opening and due to the beveled face thereof will again ride out of the opening if 10 the drum is moving in a clock-wise direction (looking downward) as will be evident from an inspection of Fig. 3. However, if the drum moves in a counter-clockwise direction as will be the case when the cord 22 15 is pulled, the right angular end of the finger 30 will engage the opening 32 and the ring 28 will be turned with the drum 20. It will be evident from the above that when the cord 22 is pulled this will cause the ring to 20 be rotated, however, upon a release of the cord the spring will cause a reverse rotation of the drum but this will not be imparted to the ring due to the dog 30 which produces a restoration of the parts to their original 25 position without affecting the position of the ring 28.

Integral with the ring 28 is a bracket 33 upon which are pivoted arms 34 and 35, these arms being pivoted on the bolt 36 about 30 which is coiled the intermediate portion of spring 37 which engages in openings in the arms 34 and 35 and acts to press them away from each other. The arms 34 and 35 are provided respectively with a member of 35 felt-like material 38 and 39 secured thereto in any suitable manner as by riveting the same between a pair of metal strips. The arms 34 and 35 bear with their felt or asbestos contact faces 38 and 39, due to the 40 action of the spring 37, respectively, against the inner surface of the reflector 12 and the outer surface of the bulb or other source of light 40.

Suitably secured to the rope 22 is a cord 45 41 connected by means of the spring tension member 42 to the chain pull 43 of the pull socket 44 mounted on the fixture 11. The cord 41 passes over a pulley 45 mounted on the arm 46 secured in any suitable manner 50 to the fixture 11 and carrying a pulley 47 over which the rope 22 passes so as to place the ring 48 on the end thereof within reach of the operator.

The entire fixture may be suitably guyed 55 if desired by a wire 49 suitably anchored in any desirable manner at 50 and secured to the bracket 51 on the fixture through a turn buckle 52 by means of which the tension on the wire 49 can be adjusted so as to prevent 60 any undesirable sidewise jerking of the fixture 11 when the rope 22 is operated.

It will be noted that when the ring 48 is pulled the rope 22 will actuate the drum 20 and as there is a certain amount of slack 65 on the cord 41 after a portion of the move-

ment of the cord 22 has taken place the cord 41 will pull the chain 43 so as to operate the switch 44 to turn on or off the light. The spring 42 is provided so that it is not necessary to adjust the slack in the cord 41 with any great nicety so as to cause the device to operate properly.

Referring now to Figs. 4 to 6 inclusive, the lighting fixture 61 comprises a light transmitting and reflecting member such as 75 a translucent glass bowl 62 provided with a suitable flange at 63 to cooperate with the flanged portion 64 of the spun metal ring 65 provided with loops or eyes 66 engaging hooks 67 on arms 68 riveted to the socket 80 housing 69. Socket 70 supports the lamp 71 connected electrically by the canopy switch 72 supported by the yoke 73 within the fixture canopy 74. The bowl 62 may be an opaque reflecting member if desired. 85

The member 75 preferably a metal spinning, closes the bottom opening in the translucent member 62, being held thereon by set screws 76 engaging in the groove 77 of said member 62. The closure member 75 supports the stationary hollow trunnion 78 on 90 which the drum 79 rotates. The drum is actuated in its rotary movement by the cords 80 which extend about the drum 79 by pulling on the ring 81 carried by the cord 82 95 secured to the cords 80 by ring 83.

The cords 80 extend over the pulleys 84 which guide them in the proper direction to engage with the drum 79, the pulleys being suitably rotatably mounted in the bottom 100 member 75.

The drum 79 is provided with a coil spring 85 secured to the drum and to the housing 75 in any suitable manner as by having the ends extend through openings 86 and 87 in members 75 and 79 respectively, the coil spring being put under tension when the drum is rotated by pulling on the cord 82. 105

The drum is also provided with spring fingers or dogs 88 which are adapted to engage with the arm 89 mounted for rotation on member 78 when the drum is moved in a counter-clockwise direction (looking down) and move the same in unison with the drum. However, when the drum is turned in the 115 opposite direction as by the spring, the arm 89 will ride over the fingers 88 and will not rotate therewith.

The arm 89 is preferably made up of two metal strips 90 and a central layer of felt-like material 91 riveted there between and extending beyond said strips. The felt portion 91 of the arm is shaped to conform to and engage closely with an inner surface of the lighting fixture such as the inner surface of the bowl 62. 120

Extending through the tube 78 is a pull cord 92 connected at one end with the ring 83 and at its other end to the chain pull 93 on the switch 72 through the medium of 125 130

coil spring 94. The coil spring is provided as to make it unnecessary to provide a very nice adjustment of the slack in cord 92, as the spring would compensate for any shortness of the cord.

When the cord 82 is pulled by the operator grasping the ring 81 the wiping arm 89 is drawn over the inner surface of the bowl 62 through the agency of cords 80 thus cleaning the same and the switch 72 is simultaneously operated through the agency of cord 92. Any dirt wiped off by the arm will drop out of the bowl through openings 95.

After the cord 82 is released the drum 79 is rotated in the reverse direction by the spring 85 and the cord is wound up thereon, however, without moving the arm 89, because of the structure of ratchet teeth 88.

In both forms of the invention described above the wiping arm travels through an arc of approximately 400° with each pull of the cord 82.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

A square metallic frame 99, preferably made of angle iron carries the transparent member 100 made of heat resisting glass. Interposed between the glass member 100 and the frame 99 are gaskets 101 of compressible material to relieve the pressure of the iron on the glass. The frame 99 is held against the under side of the reflector 12' by the toggle bolts 102 pivoted to the frame at 103 and by the hinge connection 104 securing the frame 99 to the frame 105 comprising straps extending along the sides of the reflector and connected by bolts 106 and 107. Interposed between the reflector and the glass is a felt gasket 108 provided with ventilating openings 109, covering the openings to exclude dust is a layer of open mesh bolting cloth 110.

The cleaning member 111 is provided with two vertical extensions 112, one at each end thereof. Each of these extensions have rigidly fastened thereto the rocker arm 113 which bears upon the upper edge of frame 99. The cleaning blade 111 carries a felt insert 114 clamped between the same and a strip 115 by means of bolts or any other suitable means. Secured to the cleaning member 111 in any suitable manner as by an eye are cords 116 and 117. The cord 117 passes over the pulley 118 mounted on the bracket 119 carried by the frame 105, and is provided with a spring take up 120 anchored to the spring connection 42' in the slack pull cord length 41' connected to the

chain pull 43' of switch 44' in a similar manner as the cord 41 is connected with the switch 44.

The fixture is braced at 122 in any suitable manner to prevent jerking of the same.

When the cord 116 is actuated by a pull on the rod 123 the blade 111 rocks in an anti-clockwise direction as is clear from Fig. 8

and the felt 114 comes in contact with the under surface of the glass 100 and is drawn across the same from left to right, in the drawings, wiping the dirt and dust from the same.

As the blade 111 nears the end of its travel the slack in the cord 41' is taken up and the switch 44' is operated. After relieving the tension on the cord 116 the spring 120, which has been tensioned by pulling said cord, exerts a tension on cord 117, and draws the blade 111 back to its initial position,

however, without the felt 114 coming in contact with the glass 100, due to the action of the rocker arm 113, which rocks the felt away from the glass.

It will be seen that in this form as well as in the other forms the active face of the fixture is cleaned by a wiping motion of the mechanism that takes place simultaneously with the operation of the switch. This is desirable as it insures a cleansing of the fixture whenever the light is turned on or off. It is also desirable that the wiping member always moves in the same direction across the surface to be cleaned, as a reciprocal motion fails to clean the same.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

Referring now to Figs. 7 to 9 inclusive, the lighting fixture 96 comprises a reflector similar to the reflector 12, said reflector being held on by a nut 17', a socket 18' carrying a lamp 40', a stem 16' and a switch 44' carried thereby. The collar 97 acts as an abutment for the reflector 12' and a dust cap 98 is mounted between the nut 17' and the reflector 12'.

- 42
- arm, said pull cord being connected with said operating means so as to successively rotate said arm always in the same direction by every pull on said cord.
5. In a lighting fixture, a switch, a pull cord for operating said switch connected thereto, means for cleaning said fixture and a flexible member connected with said pull cord and said cleaning means for operating 10 said cleaning means simultaneously with said switch.
6. In a lighting fixture, a switch, a pull cord for operating said switch connected thereto, rotatable means for cleaning said 15 fixture and a flexible member connected with said pull cord and said cleaning means for operating said cleaning means simultaneously with said switch.
7. In a lighting fixture, wiping means for 20 cleaning the active faces of said fixture, a ratchet mechanism for operating said wiping means, a cord for actuating said ratchet mechanism to impart successive movements always in the same direction to said wiping 25 means, and means for retracting said cord.
8. In a lighting fixture, means for cleaning the active faces of said fixture comprising 30 a sweeping arm, means for operating said arm comprising a pull cord and a connection between said arm and said operating means to move said arm successively always 35 in the same direction of movement for every pull on the cord.
9. In a lighting fixture, a socket member, a light bulb mounted in said socket member, a reflector secured in concentric spaced relation 40 to said bulb and means for simultaneously 45 cleaning the outer surface of said bulb and the reflecting surface of said reflector.
10. In a lighting fixture, a socket member, a lighting bulb mounted in said socket member, a reflector secured in concentric spaced relation 50 to said bulb and wiping arms for simultaneously cleaning the opposed faces of said bulb and reflector.
11. In a lighting fixture, a socket member, 55 a lighting bulb mounted in said socket member, a reflector secured in concentric spaced relation to said bulb, wiping arms for simultaneously cleaning the opposed face of said bulb and reflector, means for operating said arms and means to retract said operating 60 means to its original position.
12. In a lighting fixture, a socket member, a lighting bulb mounted in said socket member, a reflector secured in concentric spaced 65 relation to said bulb, spring pressed wiping arms for simultaneously cleaning the opposed faces of said bulb and reflector, means for operating said arms and means to retract said operating means to its original position.
13. In a lighting fixture, means for cleaning the active faces of said fixture, and self-restoring actuating means for said cleaning means, said cleaning means comprising a rotatably mounted arm and said actuating 70 means comprising a drum, means for imparting rotation to said drum in one direction, springs means for retracting said drum to its original position and a ratchet connection between said drum and said arm whereby a progressive wiping movement is imparted to said arm.
14. In a lighting fixture, means for cleaning the active faces of said fixture, a switch mounted on said fixture and means for simultaneously operating said switch and said cleaning means to actuate said cleaning means with every actuation of said switch, whereby said fixture is cleaned every time said switch is opened or closed to turn 80 the light on and off.
15. In a lighting fixture, means for cleaning said fixture comprising an arm adapted to be moved over the surface to be cleaned with a progressive wiping movement, self-restoring means for operating said arm, and a pull cord for actuating said operating means, said operating means producing successive wiping movements of said arm always in the same direction.
16. In a lighting fixture, means for cleaning said fixture comprising an arm adapted to be moved over the surface to be cleaned with a progressive wiping movement, a switch associated with said fixture, self-restoring means for operating said arm, and a flexible member for actuating said operating means and simultaneously operating said switch.
17. In a lighting fixture, a socket member, a lighting bulb mounted in said socket member, a reflector secured in concentric spaced relation to said bulb, an arm conforming to the inner surface of said reflector and rotatable means for supporting said arm, an arm conforming to the outer surface of said bulb mounted on said rotatable means, said arms being provided with a common pivot on said rotatable means, and a spring member engaging said arms to force said arms apart and into engagement with the reflector and bulb respectively.
18. In a lighting fixture, a socket member, a lighting bulb mounted in said socket member, a reflector secured in concentric spaced relation to said bulb, an arm conforming to the inner surface of said reflector and rotatable means for supporting said arm, an

arm conforming to the outer surface of said bulb mounted on said rotatable means, said arms being provided with a common pivot on said rotatable means, and a spring member engaging said arms to force said arms apart and into engagement with the reflector and bulb respectively, the faces of said arms

engaging the surfaces of said reflector and bulb being provided with felt-like wiping surfaces.

In witness whereof, I hereunto subscribe my name this 21st day of March A. D., 1920.

EDWIN D. TILLSON.
